UNITED STATES PATENT OFFICE

FRED M. CARROLL, OF YONKERS, NEW YORK, ASSIGNOR TO THE TABULATING MACHINE COMPANY, OF ENDICOTT, NEW YORK, A CORPORATION OF NEW JERSEY

STACKING MECHANISM FOR PRINTING MACHINES

Original application filed February 17, 1928, Serial No. 254,936. Divided and this application filed June 29, 1929. Serial No. 374,661.

This invention relates to printing mechanisms for accounting machines and the like and particularly to improvements in devices provided for the purpose of severing long strips of paper and stacking the separate sheets thus formed.

This application is a division of the parent application of F. M. Carroll, Serial No. 254,936, filed February 17, 1928.

10 In the parent application referred to provision is made for listing data and the totals thereof upon a plurality of superimposed strips. Each strip is cut into sheets of predetermined lengths for convenience in handling and filing and the present application is concerned with the provision of an improved means for accomplishing the latter function.

It is a main object of the present invention 20 to effect the feeding of a long sheet in such a manner that when severed the severed portion will assume a horizontal stacked position.

In the preferred embodiment a pair of rollers feed the strip upwardly, the free end thereof being thereafter rolled around a grid-like frame. At a certain point in the cycle of operation, the strip is severed and the tendency of the paper to assume a plane position causes the free end adjacent the severing 30 mechanism to tumble and deposit itself upon a platform. In this manner the sheets are placed in a stacked relationship.

While the present invention has been shown in connection with an accounting machine of the tabulating type it is clear that with equal facility the improvements may be applied to other types of machines and the present embodiment is illustrative rather than restrictive.

The invention will be clear from the following detailed description which should be read in connection with the accompanying drawings in which:

Fig. 1 is a sectional view of the illustrative paper severing devices and the mechanism for stacking the printed sheets shown in operated position.

Fig. 2 is a front view of the mechanisms shown in Fig. 1.

50 Fig. 3 is a view in side elevation of the

operating clutch and associated control devices in normal position.

In Fig. 1 the printed sheets 15 and 16 extend upwardly and cooperate with a pair of feeding rollers 17 which feed the strips upwardly so they pass between a stationary knife 18 and a movable guillotine knife 19. The latter is actuated at the proper time to sever these paper strips as will be described hereinafter. In the first operation of the machine, the strips are fed to assume substantially the over-hanging position indicated in Fig. 1 and drop by their own weight over a grid comprising a series of wires 20 which are anchored at their ends by a plate 21 and are bent concentric with respect to a rock shaft 22. Secured to the rock shaft 22 are arms 23 each carrying at its upper end a roller 24. These rollers are normally in the dotted line position shown in Fig. 1 and when 70 the strips have been fed pass over the ejected paper strips and roll them over the grid 20 so the free end of the strips abut the vertical sections 26 of the grid. When this position is assumed the strips are severed so that as 75 they tumble over they will be stacked on a platform 27 also of grid formation.

Rocking of the shaft 22 to roll the rollers 24 over the projected strips is preferably accomplished by clutching the shaft 22 to one 80 of the operating parts of the machine. Rotatable with a constantly rotating gear 29 is a ratchet wheel 30 (Fig. 3). Secured to shaft 22 is a disk 31 pivoted to which is a pawl 32 adapted to engage the teeth of the 85 ratchet wheel but normally disengaged by a latching pawl 33 also pivoted to disk 31. At a certain point in the cycle of rotation of a gear 400 which is turned a step for each printing operation an actuating plate 34 (Fig. 1) will 90 strike a finger 35 which is connected by a collar (see Fig. 2) to a lever 36 rocking the latter so that the upper end thereof will strike a tail 37 (Fig. 3) of latching pawl 33 and rock the latter. The released pawl 32 will now be urged by its connecting spring 39 to engage the ratchet wheel 30 as shown in Fig. 1 and thus drive shaft 22 in a clockwise direction 95 to roll the projected strips over the grid-like frame. Prior to a complete revolution of 100

disk 31 pawl 32 will strike a stationary pin 40 disengaging the pawl 32 from the ratchet wheel 30 and when this relationship exists latching pawl 33 snaps under a portion of pawl 32. Automatic return of shaft 22, in a counterclockwise direction, is effected by a coil spring 41 (Fig. 2) which is wound when shaft 22 is turned in a clockwise direction. This will bring the rollers 24 again to their normal positions shown by the dotted circle in Fig. 1 where they will be positioned upwardly over the frame 20 out of interference with the ends of the strips subsequently projected by rollers 17.

Any shocks due to the quick return of arms 23 are taken up and eased by flat springs 42 the free ends of which pass frictionally under the cross-bar to which the plate 21 is attached.

Reference character 43 designates a series of single coil spring wires carried by rod 44. Normally the free ends of these wires are above the stacked sheets permitting their free removal and are held in upward position by a spring 45 connected to a lever 46 attached to rod 44. As the right arm 23 reaches its lowermost position a roller 48 carried thereby will strike a camming edge 49 rocking lever 46 so that the spring wires 43 press against the uppermost sheet of the stack to firmly hold the stack in place. This position of wires 43 is temporarily held by a latching lever 52 the lower end of which rocks over a lug 50 when arm 46 is in its extreme downward rocked position. It will be apparent that the natural curve of the paper strips may bring the ends in interference with rollers 24 when the latter are returned by the restoration of shaft 22 so that the spring wires 43 are provided to firmly hold the strips down during the return of rollers 24 but are released as the rollers return to normal starting position. As the arms 23 and shaft 22 return to their normal starting position a cam 51 will rock the upper end of lever 52 sufficiently to unlatch the lever 52 whereupon spring 45 will raise spring wires 43 upwardly.

Guillotine knife 19 is carried by a pair of arms 53 pivoted on a rod 54. A link 55 connects one of the arms 53 to one arm of a pivoted bell crank 56 the other arm of which coats with a spiral cam 57 attached to rock shaft 22. As shaft 22 is rocked clockwise bell crank 56 will draw link 55 downward gradually, thereby bringing knife 19 against the stationary knife 18 producing a shearing action on the paper strips. The cutting action is timed to occur after the rollers 24 have rolled the projected strips over the grid frame, thus permitting the end adjacent the cutting knives to turn and deposit itself upon the stack on the platform 27.

It will be observed that the severing and stacking operations occur at a different time than the paper feeding operation.

While there has been shown and described

and pointed out the fundamental novel features of the invention as applied to a single modification it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a machine of the class described comprising in combination with means for feeding a paper strip, a stationary arcuate-shaped frame, a frame carrying a roller adapted to roll a portion of said strip over the stationary arcuate-shaped frame, and means for subsequently severing said strip whereby the sheet thus formed assumes a substantially horizontal stacked position.

2. In a machine of the class described comprising in combination with means for feeding a paper strip, an arcuate-shaped frame, a frame carrying a roller adapted to roll a portion of said strip over the arcuate-shaped frame, means for subsequently severing said strip whereby the sheet thus formed assumes a substantially horizontal stacked position, and resilient means for engaging and holding the severed sheet.

3. In a machine of the class described comprising in combination with means for feeding a paper strip, an arcuate-shaped frame, a reciprocating frame carrying a roller adapted to roll a portion of said strip over the arcuate-shaped frame, means for severing the rolled strip whereby the sheet thus formed assumes a substantially horizontal stacked position and resilient means for temporarily holding the sheet during the return movement of said roller.

4. In a machine of the class described the combination with a stationary arcuate-shaped frame with a receiving platform therebelow, of means for directing a portion of the strip over the stationary arcuate-shaped frame, and means for severing said strip whereby the detached portion assumes a plane position upon the receiving platform.

5. In a machine of the class described the combination with a stationary arcuate-shaped frame, of means for rolling a paper strip over the stationary arcuate-shaped frame so that portions of said strip are at substantially diametrically opposite points, and means for releasing one end of the strip whereby the latter assumes a plane position upon a receiving platform.

6. In a machine of the class described the combination with a stationary arcuate-shaped frame, of means for rolling one end of a paper strip over the stationary arcuate shaped frame, and means for severing a predetermined length of the strip whereby the sheet

thus formed assumes a plane position upon a receiving platform.

7. In a machine of the class described, the combination with an arcuate-shaped frame having stop portions, of means for rolling a predetermined length of a paper strip over the frame, and means for releasing the end of the strip opposite the end abutting the stop portions whereby the strip assumes a plane position upon a receiving platform.

8. In a machine of the class described, the combination with a looped frame having a receiving platform beneath the same, of a reciprocable means for directing the projected end of a paper strip over the frame whereby a portion thereof assumes a circular looped position, and means for detaching a predetermined length of the strip whereby the looped sheet thus formed assumes a plane position upon the receiving platform.

9. In a machine of the class described, the combination of means for projecting the end of a paper sheet, an arcuate shaped frame, a reciprocable device for rolling the projected end of the strip over said frame, and means for detaching a predetermined length of the sheet whereby the piece thus formed assumes a plane position upon a receiving platform.

10. In a machine of the class described, means for projecting a strip so that the free end thereof is unsupported, a circular frame, means for rolling the projected end of the strip over the frame, and means for detaching a predetermined length of the strip whereby the sheet thus formed assumes a plane position on a receiving platform.

11. In a machine of the class described in combination, an arcuate-shaped frame, a reciprocable device for rolling one end of a paper strip over the arcuate shaped frame, and means for severing a predetermined length of the strip whereby the sheet thus formed assumes a plane position upon a receiving platform.

12. In a machine of the class described, in combination, a circular frame, rollers, means for effecting a relative movement between said frame and rollers one of which is stationary during such movement to roll a record strip over the frame, and means for detaching a length of the strip whereby the sheet thus formed is free to assume a stacked position.

55. In testimony whereof I hereto affix my signature.

FRED M. CARROLL.
